UNITED STATES PATENT OFFICE.

BERNARD BRANSTON, OF BROOKLYN, NEW YORK, ASSIGNOR TO LEHMAN BROTHERS SILVERWARE CORPORATION, OF NEW YORK, N. Y., A CORPORATION OF NEW YORK.

DESIGN FOR A BEVERAGE URN OR SIMILAR ARTICLE.

Application filed March 24, 1928. Serial No. 26,000. Term of patent 3½ years.

To all whom it may concern:

Be it known that I, BERNARD BRANSTON, a citizen of the United States, residing in the borough of Brooklyn, county of Kings, State of New York, have invented a new, original, and ornamental Design for a Beverage Urn or Similar Article, of which the following is a specification, reference being had to the accompanying drawing, forming part thereof.

In the drawings Figure 1 is a side elevation, Figure 2 is a front elevation, Figure 3 is a plan view, and Figure 4 is a rear elevation of a beverage urn, showing my new design.

I claim:

The ornamental design for a beverage urn or similar article as shown.

BERNARD BRANSTON.
